UNITED STATES PATENT OFFICE.

HARRY A. HOUSEMAN, OF PHILADELPHIA, PENNSYLVANIA, ASSIGNOR TO THE STANDARD MACHINE COMPANY, OF PENNSYLVANIA.

KNITTING-MACHINE.

SPECIFICATION forming part of Letters Patent No. 595,439, dated December 14, 1897.

Application filed March 30, 1896. Serial No. 585,319. (No model.)

To all whom it may concern:

Be it known that I, HARRY A. HOUSEMAN, a citizen of the United States, residing at Philadelphia, county of Philadelphia, and State of Pennsylvania, have invented a new and useful Improvement in Knitting-Machines, of which the following is a full, clear, and exact description, reference being had to the accompanying drawings, which form a part of this specification.

The machine generally may be such as is illustrated and described in Letters Patent No. 538,518, granted to me April 30, 1895, and for general details of said machine and its operation reference may be had to said patent.

The improvement forming the basis of this application relates to a thread-carrier for a knitting-machine, and has for its object to provide a thread-carrier having two or more thread-openings, which is so connected and operated that either at the will of the operator or automatically either of the threads may be used for knitting.

I will only illustrate and describe in this specification so much of a knitting-machine as is necessary to a clear understanding of the invention forming the subject-matter of this application.

In the drawings, Figure 1 is a side elevation of knitting-cylinder, &c. Fig. 2 is a section on the line *x x*, Fig. 1. Fig. 3 is a section on line *y y*, Fig. 1.

D is the cam-cylinder.

E is the sinker-cam cylinder.

F is the needle-cylinder, and *f* the needles. The thread-carrier consists of the frame H, to which is fixedly secured the plate A, and secured to a shaft *b* is the plate B, having the thread-orifices B' and B². In the plate A is the slot *a*, in which in the movement of plate B the thread rests or travels.

C C', respectively, are leaf-springs secured to the plate A, one at each end thereof. The shaft *b* finds a bearing in and projects through the frame H and has on its end the gear-wheel or pinion H', which meshes with the rack H², connected to the arm I, which is guided and adapted to move vertically in a slot *g* in the frame H and has at its lower end the cam K. In one position of the plate B the orifice B' is in operative position in refer-

ence to the needles, and in the other position the orifice B². The plate B is caused to slide upon the plate A, so as to cause the orifices B' and B² to assume these positions by the rack H² acting on the pinion H', the rack being operated by the movement of arm I. According to which orifice B' or B² is in operative position its corresponding thread is in operative position, the idle thread in each case being held by the corresponding leaf-spring C or C'. When the plate B moves to bring the orifice out of operative position, the thread corresponding is broken off.

In practice yarns of different color or weight are drawn through the orifices B' and B², or a single thread may be drawn through one orifice and a plurality of threads through the other, which latter case, of course, would be the same as the different weight yarn thread first spoken of.

The thread-carrier as a whole may be rotated or reciprocated and changed from rotation to reciprocation in the manner and by the mechanism described and illustrated in my previous patent hereinbefore set out in this specification. The plate B is operated automatically in the operation of the machine in the following manner:

L is a supplemental pattern-chain driven by the same shaft as the pattern-chain in my previous patent hereinbefore cited. Upon this chain at desired points are raised portions *l*.

M is an angle-arm supported in suitable guide *l'* on the frame of the machine, having at one end, adjacent to the pattern-chain, the roller M' and at the other end the cam M². The roller M' is in line of movement of pattern-chain L and the cam M² in line of movement of cam K. When the roller M' is on raised portion *l* of chain, the cam K strikes the under surface of the cam M², depressing the arm I, which causes the plate B to move from the right toward the left, and when the roller is on the low portion of the chain the cam K strikes the top surface of the cam M², elevating the arm I, causing the plate B to move from the left toward the right. A spring N holds the roller M' in contact with chain L. The first movement just described brings the thread-orifice B² into operative position, and

the second movement just described brings the thread-orifice B' into operative position. Any desired number of low and high places may be placed upon the pattern-chain at the 5 points in the operation of the machine at which it is desired to change from one thread to the other.

From the foregoing it may be seen that with this construction any number of changes 10 from one to the other thread may be made during the operation of the machine. In the drawings the roller M' is shown in the high position l of the chain, and the thread-orifice B² is in operative position.

15 Having now fully described my invention, what I claim, and desire to protect by Letters Patent, is—

1. In combination, in a knitting-machine, a thread-carrier, having a portion carrying a plurality of independent threads movable upon the main portion of the thread-carrier to bring the respective threads in and out of operative position, a cam moving with the thread-carrier and connected with the movable portion 25 of the thread-carrier, a device adapted at predetermined points to be brought in line of movement of said cam whereby when said last-mentioned device strikes the cam the movable portion of the thread-carrier is shifted.

2. In a knitting-machine, in combination, a thread-carrier having a movable portion carrying a plurality of independent threads, a cam having a double surface, moving with the thread-carrier and connected with the movable portion of the thread-carrier, a device having two positions, one position in line of movement of one surface, the other in line of movement of the other surface, of the cam-operating mechanism for the knitting-machine, connection between said device and the operating mechanism whereby the position of the device is, at predetermined points, shifted, the cam being of such character that one surface striking said device shifts the 40

movable portion of the thread-carrier in one 45 direction, and the other surface striking said device shifts the movable portion in the other direction.

3. In a knitting-machine, in combination, a thread-carrier, consisting essentially of a frame, a plate secured upon a shaft having a bearing in said frame, a pinion on said shaft, a rack meshing with said pinion, an arm carried by and movable in the thread-carrier frame, and secured to or forming part of the 55 rack, a cam on said arm, and a cam having two operative positions controlled by mechanism operated by the operating mechanism of said machine in the line of movement of said pinion-arm cam and adapted in the two positions 60 to move said arm oppositely.

4. In a knitting-machine, in combination, a thread-carrier, consisting essentially of a frame, a plate secured upon a shaft having a bearing in said frame, a pinion on said shaft, 65 a rack meshing with said pinion, an arm carried by and movable in the thread-carrier frame and secured to or forming part of the rack, a cam on said arm, a secondary arm, a cam on said arm and a roller on the other end 70 of said arm, a pattern-chain having high and low portions against which chain said roller rests, the cam being in line of movement of said rack-arm cam.

5. In a knitting-machine, a thread-carrier 75 consisting essentially of a frame H, a plate fixed to said frame having springs attached to it, a second plate having a plurality of independent thread-orifices, said last-mentioned plate being movably mounted upon 80 said frame and adapted to move upon said first-mentioned plate.

In testimony of which invention I have hereunto set my hand.

HARRY A. HOUSEMAN.
